UNITED STATES PATENT OFFICE

FRANKLIN S. SMITH, OF PHILADELPHIA, PENNSYLVANIA, ASSIGNOR TO THE PRODUCTS PROTECTION CORPORATION, OF NEW YORK, N. Y., A CORPORATION OF DELAWARE

HOUSING FOR HIGH-VOLTAGE TERMINALS

Application filed March 17, 1922. Serial No. 544,640.

In the construction of high voltage terminals, such as that disclosed in my prior Patent #1,703,409, dated Feb. 26, 1929, the terminal construction includes a single slightly tapered tubular member or housing of suitable dielectric material. This material preferably consists of molded phenolic condensation product, for example, bakelite. These housings are in many cases relatively large, their dimensions or size depending upon the voltage of the apparatus, for instance, an electric transformer, in connection with which the terminal is used. The molding of the housings of the larger dimensions is relatively expensive and difficult in consequence of which it is desirable that a construction of housing be employed which will permit the employment of relatively small parts.

One of the objects, therefore, of my invention is to provide a high voltage terminal capable of highly efficient action at high voltages, of thoroughly practical construction, and embodying a housing consisting of a plurality of molded sections of a suitable material, such as a phenolic condensation product, secured together in a practical and efficient manner, which housing is adapted to be filled with gas under pressure greater than atmospheric.

Another object is to provide a high voltage terminal of inexpensive construction and moreover to provide a construction of the above-mentioned nature capable of meeting, in a thoroughly practical and efficient manner, the varying conditions imposed thereon by practical use. Another object is to provide a high voltage terminal of flexible construction, capable of inexpensive embodiment in practical form, and capable of having readily placed, in assembled relation as many standardized sections thereof as are required to withstand the intended voltage, while at the same time avoiding the necessity of a specially constructed terminal to meet desired conditions of use. Another object is to provide a sectionalized housing, for instance of bakelite, achieving such objects as above noted, and capable of effectively withstanding and

holding therein the gaseous dielectric under pressure.

Other objects and advantages of my invention will be pointed out in the detailed description thereof which follows or will be apparent from such description.

The invention accordingly consists in the features of construction, combinations of elements, and arrangements of parts as will be exemplified in the structure to be hereinafter described and the scope of the application of which will be indicated in the following claims.

In the drawing forming a part of this specification and in which I have illustrated one form of mechanical embodiment of my invention—

Fig. 1 is a longitudinal sectional view of a high voltage terminal including a housing embodying my invention and showing a portion of the apparatus to which the terminal is connected; and

Fig. 2 is an enlarged transverse sectional view taken on the line 2—2 of Fig. 1.

Referring now to the drawing, there is shown at 1 a portion of a casing of an electric transformer provided with a bushing 2 which is secured by welding within an opening through said casing. The greater portion of said bushing outside of the casing 1 is externally screw threaded as indicated at 3 to provide means whereby the inner end portion of the section 4 of the terminal housing may be secured thereto. In the construction as shown the housing for the terminal comprises two additional sections 5 and 6 which may consist of molded phenolic condensation product or other suitable dielectric material. These sections are connected together and the joint between the same hermetically sealed by means of metallic bushings 7 and 8. The bushings 7 and 8 are externally screw threaded as indicated and their opposite end portions have screw threaded connection with internal screw threads adjacent the ends of the sections 4, 5 and 6, as is shown in Fig. 1 of the drawing. For the purpose of rendering the connections between the sections 4, 5 and 6 and the bushings 2, 7 and 8 and the terminal plug 10 gas pressure tight, a suitable

cement is interposed between the screw threads of the said bushings and plug and the said sections.

Although in the construction as shown 6 three sections 4, 5 and 6 of the housing are employed it will be understood that the number of these sections may be increased or diminished as desired.

Secured in the outer end of the outermost 10 section, designated 6 in the present construction, is a terminal plug 10 in which a metallic tube 11 is anchored, the opposite inner end of which projects into the chamber of the casing 1. Said tube is concentric with the 15 bushing 2. A lead wire 12 extends into the said metallic tube 11 from the inner end thereof and its outer end is likewise anchored within the plug 10 and is also electrically connected with the said tube 11. If the voltage 20 generated by the apparatus should be relatively small, say 20 kv., requiring only a relatively short terminal structure, both of the sections 4 and 5 may be omitted. In such case a bushing 2 of proper size would be employed 25 in the larger end of the section 6. In such case the lengths of the metallic tube 11 and of the lead 12 would be correspondingly decreased.

Each of the sections is provided a short 30 distance from its inner end with an interior shoulder 15 against which the outer ends of the bushings 7 and 8 abut when the said bushings are screwed into place therein. The purpose of thus abutting the outer ends of 35 said bushings in these sections is to prevent the turning of the said bushings within said sections when the ends of the adjacent sections are being screwed onto the opposite ends of said bushings. For instance, assume that 40 it is desired to secure the adjacent ends of the sections 4 and 5 to the bushing 7; the said bushing is first screwed into the inner end of the section 5 until its outer end abuts against the shoulder 15. Thereafter, the section 5 45 being held firmly in any suitable manner, the section 4 is screwed onto the outer projecting end portion of the bushing 7. This may be done because the bushing 7 is prevented from turning by reason of the abutting of its outer 50 end against the said shoulder 15.

Although the bushings 7 and 8 have been referred to as metallic, it will be understood that if preferred bushings of non-metallic material may be employed. These bushings 55 7 and 8 constitute isolated capacities but they do not interfere with the operation of the device.

It will be seen that by my invention I have provided a housing constituting a part of a 60 high voltage terminal structure which housing includes a plurality of tubular parts or sections having their adjacent ends secured together in the manner shown or in any other known practical manner which may be preferred, thereby not only decreasing the cost 65

of construction but also providing means whereby terminals of different dimensions as may be required for apparatus of different voltages may be readily assembled from standardized parts. The practical advantages incident to such a structure will be in view of the foregoing clear and obvious. 70

While the practicing of my invention and the achievement of many advantages thereof will be clear from the foregoing, it might be noted, however, as conducive to a clearer understanding of the various features of my invention and of its action in practice that, as will be seen from Figures 1 and 2 of the drawing, the high tension lead or conducting tube 11 is held in substantially a central or concentric relation with respect to the several tubular sections 4, 5 and 6, and with respect to the several bushings, such as 7 and 8, and also with respect to the bushing 2 which is welded to the casing 1 through the wall of which the high tension energy is to be passed and from which the high tension lead or conducting tube 11 is to be insulated. This relation of the several parts, moreover, is achieved by the highly advantageous arrangement whereby, even though the housing made up of the tubular sections has to withstand the pressure of the gaseous dielectric, the high tension lead or tube 11 is relieved from having imposed upon it any of the strains or tensions necessary to maintain the tubular sections in fluid tight relation. The high tension lead or tube 11 will be seen to be free and substantially unsupported at its lower end, as is clearly seen from Figure 1. This above-mentioned advantageous arrangement is of great practical importance since, even though the insulating material, hereinabove mentioned as consisting preferably of bakelite, may have a coefficient of expansion different from that of the metal tube or high tension lead 11, the resultant different expansions or contractions of these parts in response to heat changes may freely take place without detrimentally affecting the fluid tight relation of the tubular sections of the housing or the relation, for example, of the lead 11 with respect to the bushing 2. 90

As will be further seen from Figure 1, the pressure of the gas within the housing, exerted both in an axial direction or lengthwise of the housing and in a radial direction, is resisted or taken up by the built-up housing construction itself and that the high tension conductor or tube 11, depending from the upper end of the housing, does not have to take part in resisting the pressure of the gas or in holding the sections or parts together in fluid tight relation. The permanency of the pressure-tight relation of the several parts of the housing, as well as of its connection to the container 1, is thus assured, a less expensive construction achieved than has heretofore been possible, and many 100 110 120 125 130

troubles and difficulties avoided, all without interfering with or complicating the feasibility of rapidly and conveniently assembling various sections to provide high voltage terminals of different lengths to meet the requirements of different magnitudes of voltages.

It will thus be seen that there has been provided in this invention a high voltage terminal construction in which the several objects hereinbefore noted, as well as many thoroughly practical advantages are successfully achieved.

As many possible embodiments may be made of the above invention and as many changes might be made in the embodiment above set forth, it is to be understood that all matter hereinbefore set forth or shown in the accompanying drawings, is to be interpreted as illustrative and not in a limiting sense.

Having thus described my invention, what I claim and desire to secure by Letters Patent is:

1. A high voltage terminal including a housing having a conducting lead passing therethrough and adapted to contain a fluid dielectric under relatively high pressure, said housing comprising a plurality of tubular sections of solid dielectric material about and spaced from said conducting lead and arranged in end to end relation and dimensioned to withstand the pressure of said dielectric in a radial direction, and a metallic bushing extending across the joint between adjacent ends of any two sections, said bushing being interiorly positioned with respect to said housing but spaced radially from said conducting lead and adapted to form a fluid-tight connection between adjacent sections and to hold adjacent sections in end to end relation against the pressure of said dielectric in an axial direction, the space between said sections and said lead and between said bushing and said lead being filled with said dielectric under pressure.

2. In apparatus of the character described, in combination, means forming a chamber having an opening therein; a high voltage conducting lead extending through said opening and into said means; and means for insulatingly supporting said lead with respect to said first-mentioned means and adapted with the latter to receive a fluid dielectric under relatively high pressure, comprising a housing made up of a plurality of tubular sections of solid dielectric material arranged in end to end relation and dimensioned to withstand the pressure of said dielectric in a radial direction, and a plurality of metallic means for securing one end section to said first-mentioned means, adjacent sections together, and said lead to the other section, in fluid-tight relation, said securing means being adapted to withstand the pres-

sure of said dielectric in an axial direction relative to said sections, said metallic means being disposed within the compass of said housing and those portions of the lead within the housing being spaced from said housing and said metallic means.

3. In high voltage terminal construction, in combination, a high voltage lead; an electrically conductive member having a substantially circular opening therein; means for substantially centrally supporting said lead with respect to said opening, said means including a plurality of tubular sections of solid dielectric material arranged in end to end relation, means for securing one of said sections to said member and adjacent the opening therein, metallic means for securing adjacent sections together and disposed within said sections, and means for securing said lead to the end of the section remote from said member, the interior walls of said sections and said metallic means being spaced radially from said lead; and means including a gaseous dielectric under pressure in the space between said lead and said sections and said metallic means for preventing arcing-over from said lead to said electrically conductive member by way of said metallic securing means.

4. In high voltage terminal construction, in combination, a high voltage lead; a member having an opening therein and through which said lead is to be passed; a metallic bushing secured to said member; and means for supporting said lead with respect to said bushing, said means including a plurality of tubular sections of solid dielectric material arranged in end to end relation, one of said sections being secured to said bushing, a metallic sleeve-like member securing adjacent sections together, means mounting one end of said lead in the end of the section remote from said bushing and holding said lead in spaced relation to the inside wall of said bushing, said sleeve-like member and the side walls of said sections being spaced from said lead; and means including a gaseous dielectric under pressure in the space between said lead and said sections and said sleeve-like member for preventing arcing-over from said lead to said bushing by way of said sleeve-like member.

5. In high voltage terminal construction, in combination, a high voltage lead; a member having an opening therein and through which said lead is to be passed; a metallic bushing secured to said member; and means for supporting said lead with respect to said bushing, said means including a plurality of tubular sections of solid dielectric material arranged in end to end relation, one of said sections being secured to said bushing, a metallic sleeve-like member securing adjacent sections together, means mounting one end of said lead in the end of the section remote

- from said bushing and holding said lead in spaced relation to the inside wall of said bushing, said sleeve-like member and the side walls of said sections being spaced from said lead;
- 5 a gaseous dielectric under pressure filling the space between said lead and the side walls of said sections and between said lead and said sleeve-like member and between said lead and said bushing, the radii of said lead and said bushing being proportioned to form a discharge gap adapted to break down upon a predetermined increase in voltage above normal.
- 10 6. In high voltage terminal construction, in combination, a high voltage lead; an electrically conductive member having a substantially circular opening therein; means for substantially centrally supporting said lead with respect to said opening, said means including a plurality of tubular sections of solid dielectric material arranged in end to end relation, means for securing one of said sections to said member and adjacent the opening therein, metallic means for securing adjacent sections together and disposed within said sections, and means for securing said lead to the end of the section remote from said member, the interior walls of said sections and said metallic means being spaced radially from said lead; and means for preventing spark-over from said lead to said metallic member by way of said metallic securing means comprising a gaseous dielectric under pressure in the space between said lead and
- 20 said sections between said lead and said metallic means, and a conductive member related to said lead in predetermined discharge gap relation and adapted to cause a discharge from said lead upon a predetermined increase
- 25 in voltage above normal.
- 30 40

In testimony that I claim the foregoing as my invention, I have hereunto signed my name this 13th day of March, A. D., 1922.

FRANKLIN S. SMITH.
